(57) **CLAIM**

We claim, the ornamental design for a port for aspiration device, as shown and described.

DESCRIPTION

FIG. 1 is a perspective view of an port for aspiration device comprising the new design;

FIG. 2 is left side view thereof;

FIG. 3 is a right side view thereof;

FIG. 4 is a rear view thereof;

FIG. 5 is a front view thereof;

FIG. 6 is a top view thereof; and

FIG. 7 is a bottom view thereof;

FIG. 8 is a perspective view of a port for aspiration device comprising a second embodiment.

FIG. 9 is left side view thereof;

FIG. 10 is a right side view thereof;

FIG. 11 is a rear view thereof;

FIG. 12 is a top view thereof;

FIG. 13 is a bottom view thereof;

FIG. 14 is a front view thereof;

FIG. 15 is a perspective view of a port for aspiration device comprising a third embodiment.

FIG. 16 is left side view thereof;

FIG. 17 is a right side view thereof;

FIG. 18 is a rear view thereof;

FIG. 19 is a top view thereof;

FIG. 20 is a bottom view thereof; and,

FIG. 21 is a front view thereof.

(Continued)

The broken lines depict portions of the port for aspiration device that form no part of the claimed design.
